ROAD RAIL FORM

Filed June 6, 1931

FIG. 1.

BY *Albert Grobstein*

ATTORNEY

UNITED STATES PATENT OFFICE

HAROLD L. HIRSCHHORN, OF NEW YORK, N. Y., ASSIGNOR TO STANDARD STEEL
SECTIONS, INC., A CORPORATION OF NEW YORK

ROAD RAIL FORM

Application filed June 6, 1931. Serial No. 542,607.

This invention relates to a combined road form and rail, useful in the construction of roads, concrete paving, and the like.

It is usual in the paving of roads and streets 5 with concrete or similar material, to employ a metallic form in the nature of a channeled or equivalent shaped beam to serve as a confining wall for the wet concrete and at the same time be used as a track or rail for the 10 concrete mixing or other apparatus supported upon a vehicle. Such metallic forms or rails have been secured and aligned in place by means of various devices comprising straps, stakes, and wedges for the stake to fix and 15 support the rail form in predetermined positions.

It is an object of this invention to provide a new type of means for locking a rail form to a stake for supporting the same thereby 20 in predetermined position.

It is a further object of the invention to provide a novel stake binding means which also serves as an anti-buckling support for the web of a channeled road form, and a support 25 port for the top flange thereof.

The invention comprises in combination with a channeled rail form, buttress means for directly securing and supporting the web of the rail to its base, said means serving as 30 a stake holder for wedging said form in predetermined position to a stake.

Other features of the invention will be apparent from the following description and explanation. The preferred form of the invention 35 is herein explained in accordance with the requirements of the patent statutes, but it will be understood that changes may be made without departing from the spirit and scope of the invention. It is intended, therefore, to limit the invention only in accordance with the appended claims.

In the accompanying drawing,

Figure 1 is a view in elevation of a rail form fixed in position and strengthened by 45 a plurality of my novel stake buttresses.

Figure 2 is a section along the line 2—2 of Figure 1.

Figure 3 is a section along the line 3—3 of Figure 1.

50 Figure 4 is a perspective of my novel stake

buttress in blank form before it is bent and assembled.

In the prior art, it has been proposed to insert stiffening members between the top and bottom flanges of a rail form, and it has also 55 been proposed to provide such stiffening members with straps and stake boxes to secure the form in position. In all of such prior proposals, one of the objects has been to adequately support the top flange of the form. 60 These prior proposals, however, have not been entirely satisfactory, either because they require a number of complex manufacturing operations in the fabrication of numerous parts, or else they did not provide means to 65 prevent buckling of the web of the rail, and therefore, the web had to be made of great thickness to eliminate this disadvantage. I have obviated the above disadvantages by 70 providing a buttress member which not only 75 prevents buckling of the web portion of the rail form, thus permitting a web of thin section to be used, but also serves as a support for the top rail flange, without being secured or attached thereto, thus avoiding expense in 80 assembling. The buttress member further 85 serves as a stake fixing member.

Referring to the drawing, a road rail of channeled form having a body or web 1, base flange 2, top flange 3, and depending flange 4 80 is provided with apertures 5 in the base flange thereof. Secured to the web 1 by welding, brazing, or the like, is the buttress member 6. This buttress member is preferably of channel configuration and consists of a leg portion 7 and a stake holding portion 8 forming an obtuse angle K therewith. The stake holding portion 8 is provided with an aperture 9 for receiving a stake 10 and is also provided with slots 11 for receiving a wedge 12. The 90 buttress 6 has its leg portion welded, or otherwise secured to the base flange 2 at its lower end 22, defining an acute angle R with the base flange 2. It should be noted that the buttress leg 7 is not bent around the stake 10, 95 contacting therewith only at the aperture 9 and indirectly thru the wedge 12. The wedge 12 is provided with a bolt 13 and nut 14 to serve as a stop to prevent disengagement and loss of the wedge. The buttress 100

member 6 is fabricated by notching a suitable channel iron at 15, and shown in Figure 4, forming bevels 16 and then bending the portion 8 toward the portion 7 to bring the notched or cutout edges 15 together. The slots 11 and the aperture 9 may be placed in the buttress before or after fabrication. If desired, the meeting edges of the notched portion may be welded, brazed, or the like, but ordinarily this is not necessary.

In placing the rail form in position, the wedge 12 is loosened and the stake 10 is driven into the side of the road bed 26, passing thru the aperture 9 of the buttress 6, and the aperture 5 of the base flange 2. The wedge is tightened when the rail form is adjusted to any suitable position. It will be clear, however, that the form may be positioned first and the stake driven later, or any other arrangement for placing the device in use can be made without departing from the invention.

The buttress type stake holder and strengthening member may be applied, if desired, to other rail forms. It is preferable to use the same with the channel form as shown, but the invention is not limited thereto. It will also be observed that while I have shown the buttress member provided with a certain angular arrangement in respect to the rail form with which it is used, these angles may be varied together with other details of the invention. The wedge member is placed in slots disposed between the stake 10 and the web 1, to provide a position where said wedge is out of the way with less danger of workmen tripping thereover, and by being placed in the portion 8, providing a good height from the ground with consequent better leverage. However, the wedge can be disposed on the other side of the stake 10 in the leg 7, if desired.

The angular buttress-type stake holder I have shown, by reason of its special shape and its position when assembled, not only permits easy removal of any undesirable concrete or earth accumulation around the stake, but also prevents such formation by providing a shelter about the stake.

I claim:

1. In a road rail combination, a rail member having a web portion and a base portion with a stake opening therein, a buttress channel member having a stake opening therein, said buttress member joining said web and base portions to reinforce said web portion, and said buttress member comprising a horizontal portion and a leg portion disposed at an angle to the horizontal portion, the horizontal portion being substantially spaced from the base portion and secured to the web at a top portion only of the web, the leg portion being secured to the base, a stake passing through the respective stake open-

ings of the buttress member and the base, the arrangement being such that the leg portion is substantially spaced from the web portion to provide a substantial cut-out opening therebetween, said horizontal portion of the buttress channel member being channeled in vertical cross-section and said leg portion of the buttress channel member being channeled in horizontal cross-section.

2. In a road rail combination, a rail member having a web portion and a base portion with a stake opening therein, a buttress channel member having a stake opening therein, said buttress member joining said web and base portions to reinforce said web portion, and said buttress member comprising a horizontal portion and a leg portion disposed at an angle to the horizontal portion, the horizontal portion being substantially spaced from the base portion and secured to the web at a top portion only of the web, the leg portion being secured to the base, a stake passing through the respective stake openings of the buttress member and the base, and wedge means on the buttress member securing the stake and buttress together, the arrangement being such that the leg portion is substantially spaced from the web portion to provide a substantial cut-out opening therebetween, said horizontal portion of the buttress channel member being channeled in vertical cross-section and said leg portion of the buttress channel member being channeled in horizontal cross-section.

3. In a road rail combination, a rail member having a web portion and a base portion with a stake opening therein, a buttress channel member having a stake opening therein, said buttress member joining said web and base portions to reinforce said web portion, and said buttress member comprising a horizontal portion and a leg portion disposed at an angle to the horizontal portion, the horizontal portion being substantially spaced from the base portion and secured to the web at a top portion only of the web, the leg portion being secured to the base, a stake passing through the respective stake openings of the buttress member and the base, and wedge means on the buttress member securing the stake and buttress together, the arrangement being such that the leg portion is substantially spaced from the web portion to provide a substantial cut-out opening therebetween, the horizontal portion serving as a support for the rail member and reinforcing the web portion, said horizontal portion of the buttress channel member being channeled in vertical cross-section and said leg portion of the buttress channel member being channeled in horizontal cross-section.

In testimony whereof, I hereunto set my hand.

HAROLD L. HIRSCHHORN.
